UNITED STATES PATENT OFFICE

EVERETT IRVING ROGERS, JR., OF PROVIDENCE, RHODE ISLAND

DESIGN FOR A CLIP

Application filed January 28, 1930. Serial No. 34,327. Term of patent 3½ years.

To all whom it may concern:

Be it known that EVERETT IRVING ROGERS, Jr., a citizen of the United States of America, residing at Providence, in the county of Providence and State of Rhode Island, has invented a certain new, original, and ornamental Design for a Clip, of which the following is a specification, reference being had to the accompanying drawings, forming a part thereof.

Fig. 1 is a plan view of a clip embodying my new design.

Fig. 2 is a side elevation thereof.

I claim:

The ornamental design for a clip substantially as shown.

In testimony whereof I affix my signature.

EVERETT IRVING ROGERS, JR.
